United States Patent Office

Des. 186,593
Patented Nov. 10, 1959

186,593

BLACKBOARD OR SIMILAR ARTICLE

Archie E. Warnberg, Oklahoma City, Okla.

Application April 3, 1957, Serial No. 45,565

Term of patent 14 years

(Cl. D25—1)

FIG. 1

Figure 1 is a plan view of a blackboard or similar article embodying my new design; and

The dotted line representations are for illustrative purposes only.

I claim:

The ornamental design for a blackboard or similar article, as shown and described.
